UNITED STATES PATENT OFFICE.

HENRY T. LANG, OF CLEVELAND, OHIO, ASSIGNOR TO ELECTRIC VACUUM CLEANER COMPANY, INC., OF CLEVELAND, OHIO, A CORPORATION OF NEW YORK.

BEARING STRUCTURE FOR VACUUM-CLEANER BRUSHES AND THE LIKE.

Application filed February 8, 1927. Serial No. 166,771.

The present invention relates to bearing structures for vacuum cleaner brushes and the like. Such bearing structures are usually mounted as units with the brush in the nozzle 5 of the vacuum cleaner, the brush being driven from the motor which drives the suction fan. The brush operates directly on the surface being cleaned and serves to loosen the dirt, grit and other clinging material, 10 such as threads and the like, so that the suction may remove them. The brush bearings are therefore liable to be damaged by such dirt and grit working into them and the thread-like material may often wind or wrap 15 about the brush shaft adjacent to the bearings thereby stalling the brush and causing annoyance to the user.

Ball bearings have been used extensively in connection with vacuum cleaner brushes because of their accurate construction and smooth-running qualities and because they usually require no more attention than an initial lubrication, but their use has involved 20 the use also of carefully designed protective bearing structures to meet the operating conditions and difficulties above mentioned.

In making such bearing structures dust and dirt proof, permanent press fits between the various parts have heretofore been resorted to with the result that while such structures gave satisfactory service, difficulties in the way of manufacturing and later servicing the brush assembly were encountered. For example, in the manufacturing process, if the bearing did not run true with the brush after assembly, a number of the parts had to be scrapped and the bearing was nearly always ruined in the disassembly, thereby resulting in a loss in labor 30 and material. In the field servicing of the brush, a worn or defective part made it necessary to replace the whole brush unit or at least the entire bearing assembly and the returned unit had little more than scrap 35 value, also representing a loss.

It is therefore the object of the present invention to provide an improved bearing structure for a vacuum cleaner brush which permits the safe and continuous use of ball 40 and similar accurate bearings therein under the adverse operating conditions ordinarily met with in vacuum cleaners and which may

be easily assembled and disassembled without injury to any of the parts thereof, whereby the above-mentioned manufacturing and servicing difficulties and attendant losses may be obviated.

A further object of the invention is to provide a bearing structure of the character above named which employs in its construction easily manufactured parts and a minimum number of packings which are of simple design.

For a consideration of what is believed to be novel and the invention, attention is now directed to the accompanying drawing, the following description thereof and the appended claims.

In the drawing, Fig. 1 is a front view, partly in section, of a vacuum cleaner having a brush equipped with bearings embodying the invention; Fig. 2 is a sectional view, on a much larger scale, of the improved bearing construction; Fig. 3 is a detail end view on a scale slightly larger than that of Fig. 1 of the brush supporting means; Fig. 4 is an exploded sectional view of the bearing construction shown in Fig. 2 but on a slightly smaller scale which is approximately full size; Fig. 5 is a sectional view 80 of a detail modification of Fig. 2 on the same scale as Fig. 2; and Figs. 6 and 7 are detail views of certain parts shown in Figs. 2 and 4 on the same scale as Fig. 4.

Referring to the drawing, 5 indicates a 85 vacuum cleaner having a nozzle 6 in which is mounted a brush and bearing unit 7. This unit is supported at its ends by knurled or roughened end nuts 8 which are held in slots 9 in disks 10 by means of spring fingers 90 11, the disks being suitably fixed to the end walls of the nozzle 6 by screws 12. The brush is driven by a belt 13 which runs on a pulley 14 on the brush and a pulley 15 on the end of shaft 16 of the motor which 95 operates the suction fan of the vacuum cleaner. The construction thus far described is a known one and is to be taken as typical of any suitable vacuum cleaner structure.

Referring now particularly to Figs. 2 and 100 4, 17 is the brush cylinder which is in the form of a simple metal tube provided with a wooden dowel or core 18 over which, at each end, the tube edges are rolled, as indi-

cated at 19, to firmly secure the dowel in place and prevent longitudinal movement thereof.

On each end of the brush tube is secured 5 a cylindrical bearing housing 20 which is a simple tubular member having a flanged end 21. The latter is provided with an annular groove 22. The interior of the bearing housing at one end is adapted to 10 be pressed onto the brush tube for a distance sufficient to make a firm connection therewith and being tubular and having a flange, it is easily removable therefrom if necessary without injury to itself or the 15 brush tube. At the opposite end, the interior of the bearing housing forms a cylindrical bearing chamber 23 (Fig. 4) and is counterbored to provide a shoulder 24 adjacent and spaced from the end of the brush 20 tube at the inner end of the bearing chamber. The bearing housing is also internally threaded or tapped for a short distance within the outer end of the bearing chamber, as indicated at 25.

25 Shoulder 24 forms a support for a metal disk 26 which fits the interior of the bearing chamber with a sliding fit and which forms a closure for the inner end of said chamber when seated on the shoulder. The space 30 between the disk and the end of the brush tube is filled by a packing 27 of felt or similar material, which is in the form of a simple flat disk.

Seated against disk 26 is the bearing proper 35 28, which, in the present example is a simple ball bearing having an annular row of balls held between an outer shell or race 29 and an inner race 30. The outer shell of the bearing makes a free sliding fit with 40 the interior of the bearing chamber and is held in a seated position against disk 26 by an externally threaded ring or nut 31 which engages threads 25. The nut is turned by engaging a screw driver slot 32, Fig. 45 7, with a screw driver and is tightened only sufficiently to fully seat the bearing. The thread of the nut is then lightly prick-punched, as indicated at 33, to lock the nut. This does not interfere with the easy removal 50 of the nut but prevents it from loosening by vibration.

As a cover for the bearing and to permit the nut to be easily tightened, a washer 34 is placed between it and the bearing. This 55 is similar to disk 26 and engages only the outer race of the bearing. The outer race is thus secured to the bearing housing and brush tube and rotates therewith.

The inner race 30 is stationary in operation 60 and is connected with the knurled supporting nut 8 by a fixed stud 35 which at one end is shouldered, as indicated at 36, and threaded, as indicated at 37, and which at the opposite end is reduced in diameter, as indicated at 38, to pass through the inner race.

The stud and bearing are united before assembly by placing the latter on the stud and heading over the end 38, as indicated at 39. The stud is thus held coaxial with the bearing housing and brush tube by the bearing. It 70 passes through washer 34 and bearing lock nut 31 with a loose running fit. The latter is recessed on its inner face to receive a packing washer 40 of felt or similar material which packs about the stud. The packing washer is mounted in the nut before assembly and is held therein by friction.

Between the knurled supporting nut 8 and shoulder 36 on the stud is clamped a cylindrical cup-shaped thread guard 41 which 80 surrounds and substantially encloses the flanged end 21 of the bearing housing in spaced coaxial relation thereto. The body of the stud is of such length that when mounted in the bearing housing, shoulder 85 36 holds the thread guard also in spaced relation to the end of the housing to insure a wide running clearance and provides a chamber 42 between it and the flange end. The thread guard is of such diameter that 90 the annular space between the flange and the side walls of the thread guard is only great enough to insure a running clearance between them. This provides a second chamber 95 43 of annular form between chamber 42 and the dust-laden air surrounding the brush.

The bearing is thus protected by what may be termed two dead air chambers or spaces 100 42 and 43 and a sealing packing 40, which is located between two sealing walls provided by the bearing clamping ring or nut 31 and washer 34. On the opposite side, the bearing is protected from dust or dirt, which may work down through a brush tuft and along the space between the brush tube 17 and dowel 18, by a packing provided by felt disk 27 and metal disk 26 which form practically a solid seal. The bearing is thus amply protected, at the same time being easily accessible by unscrewing the knurled nut 8, sliding 110 off the thread guard 41 and unscrewing the retaining or clamping nut 31, the assembly and disassembly relation of these parts being shown more clearly in Fig. 4.

In tightening or loosening the knurled supporting nut 8, the stud is held by holding the thread guard 41 which has a central opening 44, as shown in Fig. 6, through which the stud passes and which is flat on one side, as indicated at 45, to correspond in shape to a section 46 of the stud adjacent shoulder 36 over which section the guard is located when clamped against shoulder 36. This provides a simple and effective keying together of the two parts. The knurled supporting nut 8 is transversely divided, as indicated at 47, so that one part thereof may be tightened against the other as a locking means after the thread guard is drawn tightly against shoulder 36.

The thread guard extends over the bearing housing a sufficient distance to include the flange 21 fully within it, as shown in Fig. 2. This arrangement serves to prevent threads from wrapping about the hub of the bearing housing and climbing the shoulder 48 formed by the flange thereby eliminating this common form of annoyance.

In Fig. 5 is shown a modification of the locking means for a supporting nut which is indicated at 49. In this arrangement the locking means is a screw 50 instead of a portion of the nut as in the construction shown in Fig. 2. The threaded end 37 of stud 35 is tapped to receive the screw, and the nut is recessed to receive the screw head 51 so that the latter lies flush with the end of the nut and engages the same to prevent turning. The screw has a left-hand thread, while the nut, together with the stud, is provided with a right-hand thread. Any tendency of the nut to loosen causes the screw to tend to tighten, thus providing a simple and effective locking arrangement.

The bearing structure thus provided is as simple in construction as the brush cylinder itself which is a simple metal tube with a wooden core, and is easily attached to or removed from said cylinder. The bearing housing is a simple tubular member and the bearing being connected with the spindle or stud before assembly, is easily placed in the housing or removed therefrom by using the stud as a handle. It is a desirable feature of the arrangement that the construction permits the spindle or stud to be united with the bearing before assembly, by a simple riveting process, as no strain is transmitted to the inner race through the ball row and outer race. By this construction the inner race is not stressed because there is no bursting pressure put upon it, no drive fit is employed and the holding means is the riveted or headed end of the stud.

Furthermore, the bearing is not necessarily a ball bearing, as other suitable types may be used. It is held in the housing by a single lock ring or nut, and a simple cup-shaped stamping and nut forming the thread guard and supporting nut respectively complete the assembly. It will be seen that all of the parts are easily stamped or machined and are adapted for easy assembly.

In operation, supporting nut 8, stud 35, the thread guard 41 and the inner race 30 of the bearing are held stationary, while the brush tube or cylinder 17 bearing housing 20, disk 26, packing disk 27, retaining nut and packing 31 and 40 respectively, and the outer bearing race 29 all rotate about a common axis of the stud 35, or, more briefly, the stud, thread guard and inner race are stationary, while the housing, outer race and packings rotate with the brush.

By the construction shown, the entire bear-

ing assembly may be easily taken apart for cleaning, repair or replacement of the parts, and the entire housing may be removed from the brush cylinder to replace the brush when worn out or if damaged.

The ease with which parts may be assembled or replaced results in less manufacturing trouble and attendant cost, less service in the field because of less bearing trouble, and less difficulty in correcting any bearing trouble which may develop in the field.

What I claim as new and desire to secure by Letters Patent of the United States, is:

1. A bearing structure for vacuum cleaner brushes and the like, said structure comprising a tubular member having a flanged end provided with an annular groove, a cup-shaped member surrounding said flanged end in coaxial close running spaced relation thereto, said annular groove forming therewith an annular chamber, said cup-shaped member being spaced from the end of the tubular member to provide a second chamber between said end and the first chamber, a stud which extends axially into said tubular member through the second chamber and cup-shaped member, a bearing in said tubular member, said bearing having a radially inner rotatable member secured to the stud and a radially outer member seated in the tubular member, and means for securing said bearing member therein.

2. A bearing structure for vacuum cleaner brushes and the like, said structure comprising a tubular member providing a rotatable bearing housing, a ball bearing mounted therein, said bearing having an outer race slidably mounted in the housing and a stationary inner race, a stationary stud secured in said inner race, a disk slidably mounted in the housing forming a seat for the bearing and a closure for the housing on one side of the bearing, means forming a closure for the housing on the opposite side of the bearing, said means comprising a lock nut for the bearing and a washer both of which are mounted in the housing and which form two sealing walls, a packing between said walls, and a cup-shaped thread guard carried by the stud which encloses the housing end and forms therewith a pair of spaced substantially closed dust chambers between the bearing and the exterior portion of the bearing structure.

3. A bearing structure for vacuum cleaner brushes and the like, said structure comprising a rotatable housing, the interior of which provides a cylindrical bearing chamber having an open end and the exterior of which is provided with a cylindrical grooved flange adjacent said open end of the bearing chamber, a stud which extends axially of the chamber and projects from the open end thereof, a bearing in the chamber to which the stud is rigidly secured, said

bearing being freely movable axially of the chamber whereby it may be withdrawn from or inserted in the chamber as a unit with the stud, a clamping ring which closes the open end of the chamber and engages the bearing to hold it in the chamber, a cup-shaped member slidably mounted on the

projecting end of the stud in coaxial relation to the flange, and a threaded clamping means for holding the cup-shaped member ¹⁰ on the stud.

In witness whereof, I have hereunto set my hand this 5th day of February, 1927.

HENRY T. LANG.
